B. LARSON

JOURNAL OR WINDER SHAFT FOR PAPER MACHINES

Filed Aug. 16, 1924

*Inventor
Bennett Larson*

Watson E. Coleman
Atty

UNITED STATES PATENT OFFICE.

BENNETT LARSON, OF RHINELANDER, WISCONSIN.

JOURNAL OR WINDER SHAFT FOR PAPER MACHINES.

Application filed August 16, 1924. Serial No. 732,535.

To all whom it may concern:

Be it known that I, BENNETT LARSON, a citizen of the United States, residing at Rhinelander, in the county of Oneida and State of Wisconsin, have invented certain new and useful Improvements in Journal or Winder Shafts for Paper Machines, of which the following is a specification, reference being had to the accompanying drawings.

This invention relates to improvements in journal or winder shafts for use in the formation of paper rolls, and more particularly to that type of winder shaft shown in my prior Patent #1,033,423. In this patent I have disclosed a shaft, and more particularly a winder shaft, formed in two substantially semicircular segments connected by hinge blocks about which the sections may be moved toward or away from one another to increase or decrease the effective size of the shaft, so that the shaft may be used for winding the roll and collapsed to be withdrawn from the formed roll, thus eliminating the jamming of the roll and the necessity of splitting the same which ordinarily occurs at intervals when a solid shaft is employed.

A particular object of the invention is to provide means positively limiting the movement of the shaft sections when the same are at their maximum diameter. In the construction above referred to the sections of the shaft are shifted longitudinally of one another by means of a spring and will occasionally, through the influence of said spring, move so rapidly from an open to a closed position as to cause injury to the hands of the operator. This positive stop is for the purpose of limiting movement of the sections under influence of said spring to the point at which they are spaced apart the greatest possible distance, thus insuring that normally the shaft will be maintained at the proper size for use and thus eliminating the danger of such accidents.

A further object of the invention is to provide a modification of this structure permitting use of the same as a journal shaft, the ends of the sections being provided with trunnions for operating in the journals.

These and other objects I attain by the construction shown in the accompanying drawings, wherein for the purpose of illus-

tration is shown a preferred embodiment of my invention and wherein:—

Figure 1 is a perspective view of a journal shaft for paper machines constructed in accordance with my invention;

Figure 2 is a longitudinal sectional view therethrough;

Figure 3 is a section on the line 3—3 of Figure 2;

Figure 4 is a fragmentary side elevation, partially broken away, of a winder shaft including the stop blocks;

Figure 5 is a sectional view showing how the sections of the winder or journal shaft are collapsed upon one another to permit withdrawal of the shaft from a formed paper roll.

Referring now more particularly to the drawings, 10 and 11 are segment pieces forming the body of the shaft which may be produced in any desired manner. At intervals along the shaft, hinge blocks 12 are securely pivoted at opposite ends to the segments 10 and 11 by means of pins 13 passing through the opposite sides of each segment and through spacing blocks 14 and 14'. These spacing blocks are securely fastened to the inside of the segments 10 and 11 and have one face 15 thereof rounding to conform to the curving of the inside of the segment which they oppose. These spacing blocks maintain the hinge blocks 12 centrally located and also provide a further support for the pins 13.

In the present construction the spacing blocks 14' at one end of each section are preferably connected by a solid web 16 and this web is thickened toward the end of the section and integrally connected with the flange 17 of a trunnion 18. These trunnions are located at opposite ends of the sections, the trunnions at one end of the shaft having a flange 17 of a diameter equal to the mean diameter of the shaft when in contracted position, while the trunnion at the opposite end has a flange equal in diameter to the diameter of the shaft when in expanded position.

Arranged upon the inner surface of each section 10 and 11 is a stop block 19 in the form of an angle plate having one face 20 thereof abutting and conforming to the inner surface of the section to which the stop block is secured by rivets 21. A second face

22 is flat and extends transversely of the section and at right angles to the wall of the section. These faces 22 are of greater length than one-half the diameter of the shaft when in fully expanded position and come in contact with one another when the shaft is in this fully expanded position. This contact is assured by means of a spring 23 connecting the sections and under tension at all times. It will be obvious that a shaft of this construction will be held very firmly in its expanded position when the trunnions 18 are placed in journals 24, which are so spaced that adjacent faces of the journals abut the outer faces of the flanges 17 since relative movement of the sections at this time will be effectually prevented. Near one end of the shaft, the segments are formed with aligned slots 25, through which a lever 26 may be inserted and employed to move the shaft from expanded to contracted position.

It will be obvious that the use of the stop blocks 19 may be resorted to in the construction of the winder shaft as shown in the patent, and for the purposes of illustration I have shown such stop blocks as employed with the section of the shaft having the half collars 27 and rings or washers 28, as described in my prior patent, these half collars combining when the shaft is in fully expanded position to provide a bearing for coaction with the bearing 29 of the paper machine.

Since the device as hereinbefore described is capable of a certain range of change and modification without materially departing from the spirit of my invention, I do not limit myself to such specific structure except as hereinafter claimed.

40 I claim:—

1. The combination in a shaft of the type described of two substantially semicircular segments, pivotal connections between the sections permitting the movement of the sections into engagement with one another or into expanded positions where the sections are separated and constitute nearly a complete circle, a stop block secured to the inner surface of each section having a face extending transversely of the section and of a width greater than the radius of the complete circle formed by said segments, said faces being opposed and engaging one with the other when the segments are in expanded relation, and yieldable means connecting the segments urging said faces into engagement.

2. The combination in a shaft of the type described of two substantially semicircular segments, pivotal connections between the sections permitting the movement of the sections into engagement with one another or into expanded positions where the sections are separated and constitute nearly a com-

plete circle, a stop block secured to the inner surface of each section having a face extending transversely of the section and of a width greater than the radius of the complete circle formed by said segments, said faces being opposed and engaging one with the other when the segments are in expanded relation, yieldable means connecting the segments urging said faces into engagement, and bearings for said shaft in which the shaft is engageable when the sections thereof are in expanded position and unengageable when the sections are in contracted or partially contracted position.

3. The combination in a journal shaft of two substantially semicircular segments, pivotal connections between the sections permitting movement of the sections into engagement with one another or into expanded positions where the sections are separated and constitute nearly a complete circle, a trunnion secured to each section, the trunnions being secured to the sections at opposite ends thereof and each having a flange, the flange of one of said sections being of a diameter equal to the diameter of the sections when in expanded relation and the diameter of the other of the flanges being the same as or less than the mean diameter of the sections when in collapsed relation, and means normally holding said sections in position with the ends thereof in engagement with the first named flange and yieldably resisting movement of the section bearing the last named flange out of such engagement.

4. The combination in a journal shaft of two substantially semicircular segments, pivotal connections between the sections permitting movement of the sections into engagement with one another or into expanded positions where the sections are separated and constitute nearly a complete circle, a trunnion secured to each section, the trunnions being secured to the sections at opposite ends thereof and each having a flange, the flange of one of said sections being of a diameter equal to the diameter of the sections when in expanded relation and the diameter of the other of the flanges being the same as or less than the mean diameter of the sections when in collapsed relation, means normally holding said sections in position with the ends thereof in engagement with the first named flange and yieldably resisting movement of the section bearing the last named flange out of such engagement, and bearings for said trunnions having their inner faces spaced apart a distance equal to the spacing between the outer faces of the flanges when the sections of the shaft are in expanded relation.

5. The combination in a shaft of the type described of two substantially semicircular segments, pivotal connections between the

sections permitting the movement of the sections into engagement with one another or into expanded positions where the sections are separated and constitute nearly a complete circle, a stop block secured to the inner surface of each section having a face extending transversely of the section and of a width greater than the radius of the complete circle formed by said segments, said 5 faces being opposed and engaging one with the other when the segments are in expanded relation, yieldable means connecting the segments urging said faces into engagement, and bearings for said shaft in 10 which the shaft is engageable when the sec- 15

tions thereof are in expanded position and unengageable when the sections are in contracted or partially contracted position, the sections of said shaft being each provided at one end with a trunnion for engagement 20 in one of said bearings, said trunnions having flanges engaging adjacent faces of the bearings and fitting closely therebetween when the sections of the shaft are in expanded position to thereby prevent movement of the sections into engagement with one another. 25

In testimony whereof I hereunto affix my signature.

BENNETT LARSON.
